(57) **CLAIM**The ornamental design for an insect trap cartridge, as shown
and described.

DESCRIPTION

FIG. 1 is a front perspective view of an ornamental design
for an insect trap cartridge.

FIG. 2 is a rear perspective view thereof;

FIG. 3 is a rear view thereof;

FIG. 4 is a front view thereof;

FIG. 5 is a first side view thereof;

FIG. 6 is a second side view thereof;

FIG. 7 is a top view thereof; and,

FIG. 8 is a bottom view thereof.

The broken lines shown in FIGS. 1-8, that are immediately
adjacent to the shaded areas, and define unshaded regions,
represent the bounds of the first embodiment, while all other
broken lines are directed to environment and are for illus-
trative purposes only; the broken lines form no part of the
first embodiment.**1 Claim, 4 Drawing Sheets**(56)
